ANTI-BACK-SIPHON FLUSHING APPARATUS

Frank B. Charroin, Coronado, Calif.

Application April 11, 1938, Serial No. 201,358

2 Claims. (Cl. 4—26)

My invention relates to an apparatus for flushing toilets which will not back siphon and the objects of my invention are:

First, to provide a flushing apparatus of this class which will not overflow;

Second, to provide a flushing apparatus of this class with novel valve for the control of the water;

Third, to provide a flushing apparatus of this class with novel means for operating the water flow valve;

Fourth, to provide a flushing apparatus of this class with novel venting means;

Fifth, to provide a flushing apparatus of this class with novel water discharge apparatus;

Sixth, to provide a flushing apparatus of this class in which none of the parts will stick to prevent the normal operation of the apparatus throughout;

Seventh, to provide an apparatus of this class which is very simple and economical of construction, easy to operate, efficient in its action, and which will not readily deteriorate or get out of order.

With these and other objects in view as will appear hereinafter, my invention consists of certain novel features of construction, combination, and arrangement of parts and portions as will be hereinafter described in detail and particularly set forth in the appended claims, reference being had to the accompanying drawing and to the characters of reference thereon which form a part of this application in which:

Figure 1 is a side elevational view of my anti-back siphon flushing apparatus for toilets; Fig. 2 is a sectional view taken from the line 2—2 of Fig. 1; Fig. 3 is a longitudinal sectional view taken from the line 3—3 of Fig. 2 on an enlarged scale; and Fig. 4 is a fragmentary sectional view on an enlarged scale taken from the line 4—4 of Fig. 2 showing some of the parts and portions in elevation to facilitate the illustration.

Similar characters of reference refer to similar parts and portions throughout the several views of the drawing:

The tank body 1, tank top 2, tank bottom 3, inlet tube 4, check valve 5, vent 6, overflow and vent tube 7, discharge casing 8, operating handle 9, valve operating cam 10, release valve member 11, release valve stem 12, discharge valve member 13, discharge valve member guide and control 14, and spider member 15 constitutes the principal parts and portions of my anti-back siphon flushing apparatus for toilets.

The tank body 1 may be any shape desired, the one shown herein is cylindrical in form. Sealed in the upper end thereof by means of sealed joint is the tank top 2 which is preferably concavo-convex as shown best in Fig. 3 of the drawing. Sealed in the bottom of this tank

body 1 is a tank bottom 3 which is also concavo-convex in the preferable form. Positioned in the bottom and sealed with the bottom member 3 close to the side wall of the tank body 1 is the inlet tube 4 which is adapted to let the water 5 into the tank. This tube extends to near the top of the tank as shown best in Fig. 3 of the drawing. Mounted in this bottom 3 on the opposite side of the center from the tube 4 is an overflow and vent tube 7 which extends downwardly 10 below the bottom as shown at 7a in Fig. 3 of the drawing and its upper end is provided with a right angled bend 7b, and communicating with the upper side thereof is a vent tube 6 which extends out through the tank top 2, preferably 15 at the center, for providing a vent to the atmosphere and it is secured to the top by means of nuts 6a and 6b on opposite sides of the top forming a seal with the tank top 2 shown best in Fig. 3 of the drawing. Positioned in the extended 20 end of the portion 7b is a valve seat 7c through which is a central opening 7d, and mounted outwardly of said valve 7d in the portion 7b is a ball valve 5 which is retained by means of a cotter pin 7e shown best in Fig. 3 of the drawing, thus providing a check valve for preventing the flow of water from the tank through the tube 7, but permits the venting of the tank when the water in the tank lowers sufficiently to permit the valve 5 to open.

The bottom 3 is provided with a large central opening 3a which serves as a discharge for the water in the flushing operation. Mounted over this opening 3a on the lower side of the bottom 3 is the discharge casing 8, there being a gasket 35 8a of rubber or rubber composition interposed between the casing and said bottom. This casing is provided with a central bore 8b and the gasket 8a has a bore conforming thereto, the edge of which provides a valve seat 8c. This casing is provided with a downwardly extending cylindrical portion 8d, the lower end of which is threaded at 8e to form a connection with the toilet or other fixture for the discharge of water. This casing 8 is provided with an extended recess 8f which communicates with the bore 8b and extends outwardly past the side of the lower end 7a of the tube 7, the lower end 7a of the tube 7 being screw threaded in the casing above said recess 8f, thus providing communication 40 between the tube 7 and the bore 8b. The casing 8 is provided on the opposite sides of the recess 8f with a bore 8g in which is revolvably mounted a shank 9a of the operating handle member 9, on the extended end of which is mounted the 45 operating handle 9 which is positioned on the shank in slightly unbalanced relation as shown best in Figs. 1 and 2 of the drawing, the one end being heavier than the other and tending to turn the shank. Mounted around the shank 9a is a 50 55 60

stuffing box 9b to form a sealed joint between the casing 8 and the shank 9a. The end of the shank 9a is provided with a flat portion 9c and upon which is mounted the valve operating cam 10 which is provided with valve engaging webs 10a and 10b separated by notches 10c. It is also provided with a water engaging ledge 10d. This valve 10 is shown in position for raising the valve for providing the discharge of the water shown in Fig. 4 of the drawing and shown in released position with the discharge valve closed in Fig. 3 of the drawing.

Positioned over the opening formed by the bore 8b is a valve member guide 14 supported upon sleeves 15a shown best in Fig. 4 of the drawing which are positioned on bolts 15b which extend through the gasket 8a and into the casing 8. There are three of these bolts and sleeves as shown best in Fig. 2 of the drawing which support a spider 15 shown best in Figs. 2 and 4 of the drawing, thus providing a rigid support for the valve member guide 14. This valve member guide 14 is provided with a skirt portion 14a which extends downwardly in cylindrical form and with a concavo-convex cup shaped portion 14b which extends downwardly into the portion 14a shown best in Fig. 4 of the drawing. Reciprocally mounted upwardly and downwardly in this skirt portion 14a is the valve member 13. This valve member 13 includes an upwardly extending cylindrical portion 13a open at its upper end and adapted to fit loosely in the skirt member 14 so as to permit a slight passage between the members 13a and 14a, but the member 14a forming a guide for the valve 13 in its upward and downward reciprocation. This valve member 13 also includes the beveled angular portion 13b which forms the valve seat with the seat portion 8b of the gasket 8a. This valve member also includes a flat bottom portion 13c which is provided with a central hole 13d and surrounding this hole 13d is an upwardly extending flange portion 13e which forms a valve for the valve member 11 which is preferably rubber or rubber composition, a flat valve member adapted to rest on the flange 13e when the valve is closed. Said valve 11 is provided with a stem member 12 secured thereto by means of a bolt 11a and washer 11b. This stem is shaped as shown best in Figs. 3 and 4 of the drawing and provided with a flange 12a which extends past the sides of the opening 13d and forms a stop for the upward movement of the valve. This valve stem 12 is provided with a recess 12b in its lower end adapting it for engagement with the portion 10a of the valve operating cam 10, shown best in Figs. 3 and 4 of the drawing.

The operation of my anti-back siphon flushing apparatus for toilets is substantially as follows:

The tank consisting of the members 1, 2, and 3 is substantially filled with water through the inlet tube 4 which connects with the water service pipe or other water supply. The tank being sealed will fill except any air space that might be in the upper portion of the tank above the branch 7b of the tube 7. When it is desired to discharge the water for flushing the toilet, the handle 9 is turned with the long end up, the cam portion 10a engaging the portion 12b of the valve stem 12 and raising this valve stem until the flange 12a engages the lower side of the valve member 13 whereupon the valve member 13 is raised and telescoped within the guide member 14a until the valve reaches the position shown in

Fig. 4 of the drawing. As soon as the handle is released it drops back because the water running through the bore 8b engages the flange 10d and throws this cam into the position shown in Fig. 3 of the drawing and the flow of the water between the beveled portion 13b of the valve 13 and the valve seat 8c together with the vacuum or suction operation of the valve in the guide 14a holds the valve 13 up and in open position as shown in Fig. 4 until the water has lowered to a position that admits air below the lower edge of the apron member 14a whereupon the valve 13 will drop to closed position as shown in Fig. 3 of the drawing and the tank will immediately fill again, it being noted that the tank is vented for the discharge of the water through the vent 6 and check valve 5. However, when the water raises high enough in the tank this check valve will again close and hold the water, the valve 11 serving to properly vent the valve 13 for its telescopic action in the guide 14.

Though I have shown and described a particular construction, combination, and arrangement of parts and portions, I do not wish to be limited to this particular construction, combination, and arrangement, but desire to include in the scope of my invention the construction, combination, and arrangement substantially as set forth in the appended claims.

Having thus described my invention, what I claim as new and desire to secure by Letters Patent is:

1. In an anti-back siphon flushing apparatus for toilets, the combination of a water supply tank, an overflow and vent tube communicating with the outlet from said tank below the discharge valve and communicating with the atmosphere above said tank, a check valve in connection with said tube opening into said tank inwardly of said vent, a telescopically mounted hollow water receiving valve adapted to seat at the discharge opening of said tank, a control valve seated in said telescopically mounted hollow water receiving valve centrally of its lower side, and cam means for opening both of said control and telescopically mounted valves, said cam means provided with a water engaging flange for shifting said cam upon the discharge of water from said tank.

2. In an anti-back siphon flushing apparatus for toilets, the combination of a water supply tank, an overflow and vent tube positioned in said tank communicating with the outlet from said tank below the discharge valve and communicating with the atmosphere through the upper wall of said tank, a check valve in connection with said tube opening into said tank inwardly of said vent near the upper side of said tank, a telescopically mounted hollow water receiving valve adapted to seat in the discharge opening of said tank, a control valve seated in said telescopically mounted hollow water receiving valve centrally of its lower side and extending some distance below the same provided with a flange thereon adapted to engage the lower side of said telescopically mounted valve when shifting and opening the same, cam means for engagement with said control valve at its lower end for raising both said control valve and said telescopically mounted valve, said cam means provided with a water engaging flange for shifting said cam upon the discharge of water from said tank.
